US00D926616S

(12) **United States Design Patent** (10) Patent No.: **US D926,616 S**
 Beyrich (45) Date of Patent: ** Aug. 3, 2021

(54) **BRACELET**

- (71) Applicant: **Hypersymmetries AG**, Vaduz (LI)
 (72) Inventor: **Jens W. Beyrich**, Vaduz (LI)
 (73) Assignee: **HYPERSYMMETRICS AG**, Vaduz (LI)
 (**) Term: **15 Years**
 (21) Appl. No.: **35/508,171**
 (22) Filed: **Jun. 17, 2019**

(80) **Hague Agreement Data**

- Int. Filing Date: **Jun. 17, 2019**
 Int. Reg. No.: **DM/204237**
 Int. Reg. Date: **Jun. 17, 2019**
 Int. Reg. Pub. Date: **Dec. 20, 2019**

(30) **Foreign Application Priority Data**

- Dec. 21, 2018 (CH) 2018-00711
 (51) **LOC (13) Cl.** **11-01**
 (52) **U.S. Cl.**
 USPC **D11/6**
